UNITED STATES PATENT OFFICE.

LOUIS HOFFMANN, OF VIENNA, AUSTRIA-HUNGARY.

OIL-PRESS.

1,047,809.

Specification of Letters Patent. Patented Dec. 17, 1912.

Application filed May 18, 1912. Serial No. 698,310.

To all whom it may concern:

Be it known that I, LOUIS HOFFMANN, a subject of the Emperor of Austria-Hungary, residing at Vienna, Empire of Austria-Hungary, have invented certain new and useful Improvements in Oil-Presses; and I do hereby declare the following to be a full, clear, and exact description of the invention, such as will enable others skilled in the art to 10 which it appertains to make and use the same.

This invention relates to oil presses having a head, columns and a press ram operated by any suitable means such as a hydraulic cylinder.

According to the present invention a frame is mounted in the press provided with unperforated side walls, one or more of which are movable in the said frame in a direction normal to their faces and are forced inward by springs. The plates of the press are guided in the frame and may be either solid plates with thickened edges or each such plate may consist of two superposed half plates provided with grooves or perforations. In the upper part of the frame air ports are provided preferably on opposite sides thereof, one series of such holes being connected with an air compressor or other source of air under pressure.

The annexed drawing illustrates by way of example several constructional forms of an oil press embodying my invention.

Figure 1 is a vertical longitudinal section on the line 1, 1, Fig. 2 of one constructional form of the frame showing diagrammatically the head, the press ram and the series of press plates, only one of the side walls being movable. Fig. 2 shows a side view of the frame looking from the side of the said movable side wall. Fig. 3 is a transverse section of the frame on the line 3, 3, Fig. 2. Fig. 4 shows a modification of the part of the frame containing the air holes. Figs. 5 and 6 show details hereinafter referred to. Fig. 7 is a detail section, illustrating a modified form of press wall provided with slots, and Fig. 8 is a similar view, illustrating a further modified construction of press wall. The frame *a* has an open top and bottom and is prismatic in shape, preferably rectangular in transverse section as shown in Fig. 3 and provided with side walls *b' b' b' b'*.

In the constructional form shown in Fig. 55 1 one of the side walls *b'* is adapted to slide in guides in the frame in a direction normal to its face and is forced inward by springs *c* or the like, preferably mounted on transverse bars *k* or the like so that this side wall 60 may yield to an inward pressure. The material to be pressed is located between press plates and these are placed into the frame in which they are guided. These press plates corresponding in shape and size to the transverse section of the frame may be either full or solid plates or may be provided with grooves or perforations. Fig. 5 shows a full plate; according to this invention it has thickened edges as indicated at *i* and these 65 thickened edges force inward the material under treatment thereby permitting of a more perfect pressing and preventing the material from being squeezed out beyond the edges. Fig. 6 shows two constructional 70 forms of grooved and perforated plates each of which according to the invention consists of two superposed plates *d, e* and *d', e'*, respectively, one or either of which is provided with perforations normal to its face. According to Fig. 6, the upper half plate *d* or 75 *d'* is provided with such perforations *f* while the lower half plate is provided on its face contiguous to the upper half plate with channels, grooves or slots *g*. Fig. 6 shows 80 the two half plates separated from each other. For use the upper half plate is simply laid on the lower one, the two then forming together a press plate. The channels *g* may also be arranged in two series intersecting each other. In the upper part of the frame preferably a series of air holes *h* is provided which are connected with an air compressor or other source of air under pressure; at the opposite side of the frame 85 another series of air holes *h'* is provided. A shield *l* is arranged opposite the holes *h'* outside the frame which prevents from going to waste any oil forced out by the air current, such oil is caught by the shield and 90 flows downward along this shield and unites with the oil obtained by pressing. This shield is preferably so arranged that it is flush with the side wall at the same side of the frame when such side wall has been 95 pushed outward into the operative position indicated in dotted lines in Fig. 1 so that the oil blown out flows down together with the

oil pressed out. For charging the press the uppermost solid press plate m when such is used is removed and the press ram is slowly lowered after having been first raised to its uppermost position and as it is so lowered first a press plate, then a press cloth, then a layer of the material to be pressed, then another press cloth and then another press plate is laid on the press ram and so on until the whole frame is charged when the press ram has arrived in its lowermost position. Or the whole pile of superposed press plates, press cloth and material may be built up outside the frame and then as an entirety put into the same. The number of press plates and layers of material so superposed depends on the height of the frame and the desired thickness of the oil cakes. Finally the uppermost solid press plate m is placed on the pile and thus the top of the frame is closed. When solid press plates are employed in the construction of the frame shown two of the side walls, for instance b^2 and b^4 are rigidly held in position in the frame by stops or the like, so as not to yield to internal pressure while side walls b^1 and b^3 are held in position by springs c . When grooved plates, such as shown in Fig. 6 are used preferably only one of the side walls is held in position by springs as shown in Fig. 1 so that only this one side wall can yield to internal pressure. On commencing the pressing the movable side wall or walls are pushed outward preferably by any convenient mechanical means so far that the oil pressed out can flow off at once and the movable side wall is flush with the shield as shown by dotted lines in Fig. 1. If now the press ram is forced upward in the frame by any suitable means such as hydraulic pressure the oil is pressed out from the material and escapes toward the movable side wall or walls which owing to their being held in position by springs can yield so that the oil may escape freely and flow downward along the movable side wall or walls. When solid press plates are used two movable side walls are sufficient in the case of grooved press plates one movable side wall only is required. When it is desired to discharge the frame the pile consisting of press plates and oil cakes is raised out of the frame gradually after the removal of the uppermost solid press plate m the press plates and oil cakes being pushed out laterally the one after the other as they come above the top of the frame. When grooved press plates are used air under pressure is blown through the air holes h whereby whenever a grooved press plate comes opposite the said air holes currents of air rush through the grooves or channels g in the press plates thus driving the oil accumulated in these grooves or channels through holes h' opposite the holes h the movable side wall b' and this oil first strikes against

the shield l whereby loss of oil is avoided and then flows down along the movable wall b' the air escaping together with the oil.

In the modification shown in Fig. 7 press plates with channels are used and the side walls b^2 b^4 opposite the ends of the channels n of the press plates are provided with vertical slots o opposite the ends of the said channels and located in vertical planes passing through such channels. When the press is in action the oil forced out escapes through the channels n and through the slots o to the outside of the side walls where it flows down and is led off by suitable channels p at the bottom of the side walls.

The modification shown in Fig. 8 differs from that shown in Fig. 7 only in that the slots extend throughout the height of the side walls and in this case the side walls may be built up of vertical rods q , the spaces left between adjacent rods constituting the slots.

In the case of the modifications shown in Figs. 7 and 8 all the side walls may be made stationary so that the movable side walls are entirely dispensed with, whereby the construction of the press is considerably simplified.

Of course each press plate may be provided with two series of channels at right angles to each other, one of such series being on the one face and the other on the opposite face of each press plate, or both series of channels being on the same face of the press plate. All four side walls of the press are then slotted as shown in Fig. 7 or 8.

Fig. 4 shows a modified construction of the air holes h' , their outer ends lead into vertical downwardly extending slots or into a horizontal channel common to all of them, such slots or channel being open at their bottom. The outer wall of these slots or channel then acts in the same way as the shield l hereinbefore described and the movable side wall is more perfectly guided. Preferably press cloth is laid on the press plates in the well known manner; in case of solid press plates the oil flows out through this press cloth.

The combined press plates above described and constructed according to the present invention offer the advantage that after separating the half plates constituting them they can be readily cleaned. The thickened edges of the press plates secure an efficient squeezing inward of the material and prevent the latter from being forced outward beyond the edge of the press plates. Owing to the construction of the press as an entirety the press plates are reliably guided and the oil pressed out can flow off freely without any losses, the elastically supported movable side walls receding, if required. The side walls can be readily removed and cleaned. If combined press plates are used each lower press cloth may be lined with a fine mesh filter.

cloth for preventing particles of the material pressed from entering the grooves or perforations of the combined press plates.

Claims:

- 5 1. In an oil press the combination of a head plate, a press ram, a frame interposed between the head plate and the press ram, the latter being adapted to enter such frame provided with a series of parallel channels in at least one of its faces, side walls rigidly mounted in the frame opposite the ends of the said channels and provided with vertical slots extending throughout the height of the side walls in the vertical planes of such channels and air ports provided at opposite sides in the upper part of the frame and adapted to come opposite the ends of the channels whereby air under pressure can be blown through the said channels, substantially as and for the purpose described.
- 10 2. In an oil press the combination of a head plate, a press ram, a frame interposed

between the head plate and the press ram, the latter being adapted to enter such frame, 25 press plates guided in the frame provided with a series of parallel channels at least on one of its faces, side walls rigidly mounted in the frame opposite the ends of the said channels and provided with vertical slots 30 extending throughout the height of the side walls in the vertical planes of such channels and air ports provided at opposite sides in the upper part of the frame and adapted to come opposite the ends of the channels whereby air under pressure can be blown 35 through the said channels, substantially as and for the purpose described.

In testimony whereof, I affix my signature, in presence of two witnesses.

LOUIS HOFFMANN.
